UNITED STATES PATENT OFFICE.

WESTON M. FULTON, OF KNOXVILLE, TENNESSEE, ASSIGNOR TO THE FULTON COMPANY,
OF KNOXVILLE, TENNESSEE, A CORPORATION OF MAINE.

FLUSH-TANK.

1,203,602.

Specification of Letters Patent. Patented Nov. 7, 1916.

Application filed April 28, 1914. Serial No. 834,974.

To all whom it may concern:

Be it known that I, WESTON M. FULTON, a citizen of the United States of America, and a resident of Knoxville, Tennessee, have 5 invented a new and useful Improvement in Flush-Tanks, which invention is fully set forth in the following specification.

This invention relates to flush tanks and more particularly to flush tanks of the 10 siphon discharge type, in which the siphon is connected to the discharge pipe by means of a flexible metal section.

My invention has among its objects to reduce the time required for immersion and 15 for filling of the siphon, thereby starting the siphoning action quicker; to remove unnecessary strains from the bellows connection by taking the weight and its associated means off this connection and by reducing and 20 regulating the throw of the siphon during its movements; and further, to generally improve the structure of this type of tank discharge, whereby its efficiency and durability may be increased.

25 With the above objects in view, my invention, broadly stated, consists in providing a siphon larger at its inlet end than at its outlet, and having a cross section at the bend, the vertical dimension of which is 30 shorter than the horizontal dimension, and in providing bearings for supporting the weight of the siphon tube and its parts and adjustable limiting means for confining the 35 swinging up and down of the siphon tube on its bearings within limits suitable for immersion and preventing undue strains of the bellows connection.

The siphon may assume, under the above form, various shapes, but the one which I 40 have found efficient is one having a cross section in form of a parallelogram beginning at the mouth of the siphon and extending to a point somewhat beyond the bend where it merges into a round cross section 45 terminating preferably with a flange for attachment to the bellows connection. At the bend the shorter dimension of the cross section is vertical, the purpose of which is to shorten the stroke necessary to immerse the 50 siphon in order to fill it, thereby reducing the amplitude of swing and the strain on the bellows while also securing a quicker starting action due largely to the admission of a larger volume of water to the flattened 55 bend.

The bellows or flexible connection is preferably in the form of a corrugated collapsible and expansible metal tube, one end of which is made fast to the end of the discharge pipe in the tank and the other end to 60 the flanged end of the siphon tube. Various means may be used for limiting the swinging movements of the siphon. The one illustrated and the one which I prefer 65 consists of a rod, the threaded ends of which pass freely through holes in flanges, one of which is on the discharge pipe and the other on a part of the swinging siphon. Heads or nuts on the rod confine the flanges between them and limit the swinging movement in one direction. Movement in the opposite direction is limited by a sleeve placed 70 on the rod between the flanges. The vibratory swings of the siphon are thus controlled between the limits determined by the 75 distance necessary for immersion of the shallow bend in the siphon, and the corrugated walls of the bellows move equally on both sides of its swing and to an extent just sufficient for filling the siphon, thereby protecting the corrugations from unnecessary 80 strains.

For the purpose of relieving the bellows from the weight of the siphon tube and other parts, revoluble bearings are provided 85 to support these parts. The axis of support is preferably located between the ends of the bellows and near a middle point. This support not only helps to relieve the strain, but gives a fixed and definite fulcrum on which 90 to balance and swing the siphon.

In order that the invention may be more clearly understood, reference is had to the accompanying drawings, which illustrate, 100 by way of example, one mechanical expression of the inventive idea, but such drawings are intended only to assist the description and not as defining the limits of the invention.

Figure 1 is a vertical sectional view 105 through a flush tank provided with my improvements; Fig. 2 is a perspective view 110 somewhat enlarged, showing the means for taking the weight of the siphon tube off the bellows connection; Fig. 3 is a view partly 115 in elevation and partly in perspective, showing the parts separated; and Fig. 4 is a perspective detail view showing the siphon pipe 120 deflected.

Referring to the drawings, 1 designates a 125

flush tank provided with a feed pipe 2 and a discharge pipe 3. The feed pipe 2 connects inside the tank with a pipe 4 near the top of which is connected a depending pipe 5 for delivering the water near the bottom of the tank and a pipe 6 conducting water to the discharge pipe 3 for filling the hopper after each discharge.

7 is a float which operates a valve in the supply pipe through suitable connections 8. A siphon 9, preferably of my improved construction, is connected through bellows 10, such as a flexible corrugated metal tube, with an offset pipe 11 delivering into the tank discharge pipe 3. The flexible corrugated connection 10 is provided with necks 12, 12' each ending in a flange 13, 13'. The offset pipe 11 is also provided with a flange 14 to which flange 13', on the flexible connection, is secured by means of the two halves of a split ring 15 adapted to fit around the neck 12' and be bolted to flange 14, a washer 16, provided with suitable holes to receive the bolts, being interposed to make a tight joint. The opposite flanged end 13 of the flexible connection 10 is secured to the flanged end of the siphon tube between a split ring 17 on neck 12 and a ring 18 on the siphon tube. Ring 18 may be, and preferably is, split for the purpose of placing it around the siphon tube and when a split ring is used the parts are arranged to break joints with split ring 17 on the neck of the flexible tube. A tight joint is formed by interposing a washer 19, and the parts are clamped together by bolts or screws in a well known manner. Should ring 18 be made integral, the flange terminating the siphon tube is made after the ring 18 is placed on the tube. The ring 18 is provided with arm 20 for the attachment of operating devices. Through flanges 14, 15, 17 and 18, and in line with each other, holes are provided for loosely receiving a limiting rod 21, slightly longer than the normal length of tube 10. One or both ends of this rod are threaded to receive nuts 22 which limit the swing of the siphon in one direction which, in the illustration, is the downward or immersion swing. To limit the upward swing, I preferably employ on rod 21 a sleeve 23, which is somewhat shorter than the distance between the flanges on the flexible connection. An upward movement of the siphon brings flange 17 against the end of sleeve 23 and terminates its movement.

It is to be understood that I do not wish to be limited to the specific form of limiting means, as the same result may be secured in other ways, provided the sidewise swings of the vessel are limited.

In order to support the weight of the siphon and its attachments, while permitting a rocking movement to the flexible connection, two pairs of oppositely disposed hinges

are provided, each pair consisting of a member 24 secured to the ring members 15 which in turn are secured to the end of the pipe 11 and a companion member 25 secured to the ring 18, the axis of the hinges being located preferably about the middle of the length of the flexible connection and properly positioned to permit the siphon to swing in a vertical plane. The siphon is normally kept in its elevated position by counterbalancing means, such as by a spring or weight. Both means are illustrated. On the bend of pipe 11 is formed a lug 26 to which one end of a spring 27 is attached, the opposite end being secured to a threaded eye-bolt 28 which passes through an opening in arm 20 and is made fast to the arm by a nut 29 and a thumb screw 30. The tension of the spring is adjusted by means of the nut and screw. In lieu of the spring a weight may be used, such as weight 32 on the operating lever 33 acting through link 34, the lower end of which may be attached to one of the wings of the thumb screw, as illustrated, or both the weight and spring may be used.

The siphon tube is peculiarly adapted to operate with the controlling means associated with the flexible connection and is illustrated on a reduced scale in Fig. 4. The receiving leg 35 of the siphon is made flat rectangular in cross section and continues in this form over the bend 36 and to a point beyond the bend where it begins to reduce in size and merge into a circular flanged termination on the delivery leg. This construction provides a shallow bend measured vertically, while having a sectional area larger than the delivery opening of the siphon. This form of tube enables a slight rise of water in the bend to fill the tube and start flow quickly and also enables a small flexing movement of the bellows connection to immerse the bend, which is of decided importance in this connection.

Outside the tank is provided the usual operating means such as a handle 37 for lifting a shaft 39 carrying a lever 40 having a pin 41 working in a slot in the end of lever 33 which is fulcrumed at 42. The lever 33 is provided with prongs 47 which engage shaft 39 to limit the extreme movement of lever 33.

The operation of the device is as follows:— After the tank has been filled and the supply cut off, in the usual manner, by the automatic cut-off means, the water stands in the tank at the level indicated and the hopper has been filled through pipe 6. The siphon 9 stands in the upper dotted line position under the action of spring 27 and ready for flushing. The handle 37 is moved to the left thereby lifting link 34 and arm 20 extending from flange ring 18 on the siphon tube 9 which now swings downward on its hinged support. Water now fills the

- shallow bend 36 which is immersed by the movement and starts the siphon action which continues after the handle 37 is released and the spring 27 lifts the parts to their original position. It will be noted that the end of the bellows moves in a true circle, the center of which is in the axis of the hinge supports and that the angle through which it moves is limited in one direction by the limiting rod 21 and nuts 22 and in the opposite direction by the ends of sleeve 23 and that by proper adjustment of the nuts on rod 21 the angle on both sides of the longitudinal axis of the vessel may be equal and limited to the short distance necessary to immerse the bend, thereby limiting the amount of flexure of the bellows to a minimum and distributes equal wear on both sides of the vessel.
- 20 1. What is claimed is:
1. In a flush tank, a discharge pipe, a siphon tube, a flexible tubular connection between said elements, flange means for securing the connection to said pipe and tube, and means for flexing said connection and limiting means consisting of a rod and sleeve between the ends of which said flange means has a play for limiting the flexure of said connection.
  2. In a flush tank, a siphon tube therein having a horizontally flattened bend, the shorter leg of the siphon including the bend having a sectional area which is larger than that of the delivery end of the tube, a flexible corrugated metal tube connected to said delivery end, hinge members for directing the flexure of said last named tube about a point between the ends of the same, resilient means normally acting on the siphon to hold it in a raised position, and means for limiting the flexure of said tube on both sides of its normal position.
  3. In a flush tank, the combination of a discharge pipe, a siphon tube, a flexible corrugated metal tube connecting said siphon and pipe, and means for limiting the flexure of said connection comprising a member fast on one of said inflexible sections and a rod having stop means loosely engaging said member and fast to a stationary part at its opposite end.
  4. In a flush tank, the combination of a discharge pipe, a siphon tube having a hinged support on said pipe, yielding means for normally holding said siphon in a predetermined position, a flexible corrugated metal tube connecting said siphon and said pipe and means comprising rigid members fast to said siphon and pipe and a rod provided with stop means having loose engagement with one of said members and held by the other member for limiting the flexure of said flexible connection.
- 5 10 15 20 25 30 35 40 45 50 55 60 65 70 75 80 85 90 95 100 105
- metal tube connecting said siphon and said metal pipe, and means comprising rigid members fast to said siphon and pipe and a rod provided with stop means having loose engagement with one of said members and held by the other member for limiting the flexure of said flexible connection.
5. In a flush tank, the combination of a discharge pipe, a siphon tube and a corrugated metal tube connected between said elements, an adjustable yielding means having a connection to said siphon for normally holding said tube in a predetermined position, a rod provided with stop nuts and supported on said tube and pipe for limiting the flexure of said connection in one direction and a sleeve on said rod for limiting the flexure of the connection in the opposite direction.
6. In a flush tank, the combination of a discharge pipe, a siphon tube having a flexible corrugated metal tube connection with said pipe and a hinged support for said tube, a rod having stop means and supported on said tube and pipe for limiting the flexure of said connection in one direction and a sleeve on said rod for limiting the flexure in the opposite direction.
7. In a flush tank, the combination of an outlet pipe, a siphon tube having a flattened bend the cross-section of which is larger than the outlet, and provided with a hinged support on said pipe, yielding means normally holding said siphon in a predetermined position, a flexible corrugated tubular connection between said siphon tube and pipe and a rod having stop means supported on said tube and pipe for limiting the flexure of said connection in one direction and a sleeve on said rod for limiting the flexure in the opposite direction.
8. In combination a siphon having a flattened bend, the shorter leg of the siphon including the bend having a cross section which is larger than that of the delivery end and a flexible corrugated metal tube connected to the said delivery end to enable the immersion of the bend for filling.
- In testimony whereof I have signed this 105 specification in the presence of two subscribing witnesses.
